The ornamental design for adjustable transverse engine support, as shown and described.

DESCRIPTION

FIG. 1 is a front elevational view showing my new design for an adjustable transverse engine support;

FIG. 2 is a side elevation view of the apparatus with its opposite side being a mirror image thereof; and,

FIG. 3 is a top view thereof.

The difference between the appearances of the front view and the undisclosed rear view is that no extending structure is abutting the surface of the rear view.
